INVENTOR
ABRAHAM GOLDENBERG,
BY
Irving Seidman
ATTORNEY

This invention relates to a machine for stitching or stapling together sheets of paper or similar material and has particular reference to such a machine constructed of a minimum number of parts which are held together, in operable order, by means of removable locking pins.

An object of this invention is to provide a stapling machine of the character described comprising parts which may be cut from a single piece of material and then pressed and formed into the required shape.

Another object of this invention is the provision of a stapling machine of the character described, wherein the principal parts of the machine are assembled and held together, in operative arrangement, by means of pins which may be readily removed to disassemble the parts, to effect replacements or repairs.

A further object of this invention, is to provide a stapling machine of the character described, wherein means are provided to dislodge or discharge from the machine, staples which may become deformed and useless, and prevent jamming the working parts.

A still further object of this invention is the provision of a stapling machine, of the character described, wherein the principal parts of the machine are specially designed to permit die cutting same from single pieces of material and forming same to the required finished shape.

A still further object of this invention is the provision of an organization in which the constituent elements are so arranged structurally and functionally as to assure improved results with materials and members which may be manufactured at reasonable cost, may be easily assembled and which will be efficient in operation with minimum wear to the parts.

The best embodiment of the invention has been chosen for illustrative purposes, but this embodiment should be viewed as being illustrative only and not as limiting because obviously the invention is capable of other embodiments having revised details of construction, so long as they fall within the ambit of the appended claims.

The invention itself, however, both as to its organization and its method of operation, will best be understood from the following description of a specific embodiment when read in connection with the accompanying drawings, in which:

Fig. 1 is an exploded perspective view of the machine, with a part broken away.

Fig. 2 is an elevational view of a part of the machine looking in the direction indicated by the arrow A of Fig. 1.

UNITED STATES PATENT OFFICE

2,574,697

STAPLING MACHINE

Abraham Goldenberg, Brooklyn, N. Y.

Application November 16, 1949, Serial No. 127,719

3 Claims.

(Cl. 1-3)

1

This invention relates to stapling machines for stitching or stapling together sheets of paper or similar material and has particular reference to such a machine constructed of a minimum number of parts which are held together, in operable order, by means of removable locking pins.

2

Fig. 3 is an elevational view of another part of the machine looking in the direction indicated by the arrow A' of Fig. 1.

Fig. 4 is an elevational view of still another part of the machine looking in the direction indicated by the arrow A'' of Fig. 1.

Fig. 5 is a fragmentary detail, in elevation, of one end of the staple holding bar of the apparatus, and shows parts in section. Fig. 6 is a similar view but showing a deformed staple about to be dropped or discarded. Fig. 7 is a plan view of the bottom portion of same.

Fig. 8 is an elevational side view of the assembled stapling machine.

Fig. 9 is a plan view of same.

Fig. 10 is a front elevational view of the stapling end of the machine.

Fig. 11 is an elevational view of the opposite or rear end of the machine.

Fig. 12 is a sectional elevational view of the stapling end of the machine and is taken along the line 12-12 of Fig. 9.

Fig. 13 is an enlarged sectional plan view taken along the line 13-13 of Fig. 12, looking in the direction indicated by the arrows.

Fig. 14 is a sectional elevational view taken along the line 14-14 of Fig. 13 showing a part of the forward portion of the machine, with a part broken away.

Fig. 15 is a fragmentary detail showing a plan view of the rear end of the base member of the machine; a pivotal upper part of apparatus being removed. Fig. 16 is a transverse section, in elevation, of same, taken along line 16-16 of Fig. 15, and Fig. 17 is a longitudinal sectional view of same, taken along line 17-17 of Fig. 15 and shows the rear end of the pivotal member attached.

Referring in detail to the parts, 11 designates 40 a base member having a slightly depressed portion at its rear end forming a shelf 12 to which are attached upstanding cheek pieces 13 having perforations 14 formed therein. A bar 15, channel shaped in cross section and having depending lugs 16, perforated at 17, is pivotally connected to the cheek pieces 13.

A removable pin 18 (shown in Figs. 8, 9, 10 and 11), engages through the perforations 14 and 17 and pivotally ties the channeled bar 15 to the base member 11.

The rear end of the base member is further formed with a cut out portion or slot 11' extending inwardly and slightly beyond the perforations 14 formed in the cheek pieces 13, and provides a passage for the said pivotally connected channeled bar 15 when same is turned about its pivotal connection at 18 to a point approximately

180° with the base member, in which position the apparatus may be used for tacking purposes (see Figs. 15, 16 and 17). A tight or snug frictional contact between the sides of the bar 15 and the walls of the opening 11' will hold same in its extended position. A flat or leaf spring 19 is secured to the base 11 and engages beneath the channeled bar 15 to urge same to its normal position as shown in Fig. 8. The side walls 20 of the channeled bar 15 (Fig. 14) are formed with inwardly extending flanges 21 to form a slot 22 extending the full length of the channeled bar 15.

An inner channeled member 23 is secured to the channeled bar 15 between the walls 20 thereof and functions as a runway or guide for a strip of staples 24 (Fig. 12). A follower or staple pusher 25 slides upon the inner channeled member or staple guide 23 and is urged forward against the strip of staples 24 and feeds same toward the stapling end of the machine. A hook or attachment member 26 is secured to the staple pusher 25 and receives a loop 27 secured to the outer or free end of a coiled spring 28 mounted within a housing 29 secured upon the channeled bar 15 near the stapling end of same. The housing 29 is formed with two side walls 30 and a front wall 31 and is welded or otherwise secured to the channeled bar 15. The front wall 31 of the housing 29 is formed with cut and pressed out lugs 32 which engage in a slot 33 formed upon hollow plunger element 34. The plunger 34 slidably engages against the front wall 31 of the housing 29 and is formed with a front wall 35, side walls 36 and a rear wall 37 in which the slot 33 is formed (Figs. 1 and 4). The rear wall 37 of the hollow plunger 34 has slidable contact with the front wall 31 of the housing 29 and the front wall 35 of the hollow plunger 34 lines up flush with the front end 38 of the channeled bar 15 (Figs. 1 and 12).

The hollow plunger 34 is further provided with a top formed by the turned in upper ends 39 of the sides 36. The top formation extends rearwardly beyond the rear wall 37 to form an offset 40 which, coacting with the top of the housing 29, limits the downward movement of the hollow plunger 34. Threaded perforations 41 are provided in the top 39 in which screws 42 engage to hold in place a pressing knob 43 (Fig. 12). A spring 44 is housed within the hollow plunger 34, has contact with the top 39 of the hollow plunger 34 and seats upon a block or plate 45 which in turn rests upon the flanges 21 formed upon the side walls 20 of the channeled bar 15. The plate 45 is formed with a cut and pressed out lug 46 which receives the lower end of the spring 44 (Figs. 1, 12 and 13).

A staple driver blade 47 is securely fastened to the front wall 35 of the hollow plunger 34 by means of a rivet 48 or by any other suitable method. The lower end of the staple driver blade 47 extends below the lower end of the hollow plunger 34 a distance sufficient to bring the lower end of the staple driver blade 47 to a point just above the top of a staple aligned beneath the staple driver blade when the hollow plunger 34 is in its normally raised position as illustrated in Fig. 12.

An outer shell or casing 49, open at its front end 50 and formed with a rear end 51 partly open, as at 52 (Figs. 2 and 14) fits snugly over the housing 29 and the stapling end of the machine and extends downwardly to lower edge of the channeled bar 15 and forwardly to the front end of the channeled bar 15, as shown in Fig. 12, and

10 by the broken projection lines in Fig. 1. In this position, detachable pins 53, which engage through perforations 54 in the outer casing 49 and coinciding perforations 55 in the housing 29, hold the outer casing 49 securely in place. The hollow plunger 34 and its spring 44 may rest in its designated position but may be readily removed. The outer casing 49 is formed with pressed out beads 56 extending vertically upon the sides, near the front ends thereof.

15 A front sliding closure member 57, having a front wall 58, sides 59 and open at the rear, is formed upon its sides 59 with pressed out beads forming grooves 60 which conform to and coincide with the outer surface of the beads 56 upon the outer casing 49. With the hollow plunger 34 and its enclosed spring 44 in position, the closure member 57 slides over the outer casing and securely holds in place the reciprocally movable hollow plunger 34 (Fig. 8). Upon the inside of the front wall 58 (Figs 2 and 13) of the slidable closure member 57 there is formed a recess or groove 61 which provides a track or guide way for the staple driver 57 and a groove 62, extending part way down the inside of the front wall provides a clearance for the head of the rivet 48 which secures the staple driver 47 to the hollow plunger 34.

20 An anvil plate or disk 61 is provided and rests in a recess 62 wherein it is held by the urge of a spring 63 engaging around a pin 64 secured to the anvil plate 61. The spring engages between the head 65 and the bottom 66 of the recessed portion 62 through which the pin 64 freely passes. One or more indentations or depressions 67 and 25 68 are formed in the anvil plate 61 which may be pushed upwardly against the urge of the spring 63 and turned to align the desired indentation with the driver blade depending upon the staple leg deformation desired (Fig. 12).

30 If due to wear or for any other reason, a second staple leaves the stack when the staple blade is brought down (Figs. 5 and 6) the second staple will be forced rearwardly in the machine, fall into staple discharging slots 69 and drop from the stapling machine thereby preventing the jamming of the machine.

35 To remove the sliding closure member 57 the pressing knob 43 must first be removed or when the channeled bar 15 is elevated about its pivotal connection to clear the base 11, the sliding closure member may be slid off toward the bottom.

40 To disassemble the machine the pins 53 engaging through the outer casing 49 and the housing 29 at the stapling end and the pin 18 at the rear pivoting end may be easily withdrawn.

45 Due to constant use of the machine, the contacting surfaces of the slidable closure member 57 and the casing 49 may wear and thereby reduce the frictional contact between the opposing surfaces and prevent the proper positioning of the closure member. When this occurs the frictional contact may be increased by bending and spreading apart the open ends 50 of the casing 49 by contracting or bending together the open ends of the slidable closure member 57.

50 I claim:

55 1. In a stapling machine of the character described the combination of a housing having front and side walls secured to the stapling machine, lugs formed upon and extending outwardly from the front wall of said housing, a hollow plunger slidably engageable against the front wall of said housing and formed with a longitudinal slot adapted to engage the said lugs upon the

front wall of the said housing, a spring within said hollow plunger to urge same upwardly, a staple driver secured upon said plunger, an outer shell having open front ends, slidably engageable over said housing, removable pins engageable through said outer shell and housing to lock same together, and a closure member slidably engageable over the open front ends of the said outer shell and adapted to hold the said plunger in position.

2. In a stapling machine of the character described and as set forth in claim 1, wherein the outer casing is formed with pressed out guide beads and the closure member is formed with pressed out grooves coinciding with and engaging over the beads upon the outer casing.

3. In a stapling machine of the character de-

scribed and as set forth in claim 1, wherein the casing has flexible open ends which may be bent outwardly to increase the frictional contact of the closure member upon the casing.

ABRAHAM GOLDENBERG.
